US00D856959S

(12) **United States Design Patent** (10) Patent No.: **US D856,959 S**
(45) Date of Patent: ** *Aug. 20, 2019

(54) **ELECTRONIC DEVICE**

- (71) Applicant: **Samsung Electronics Co., Ltd.**, Suwon-si (KR)
- (72) Inventors: **Jae-Hun Seo**, Suwon-si (KR); **Hyok-Su Choi**, Seoul (KR); **Hyoung-Shin Park**, Seoul (KR); **Yun-Jin Kim**, Seoul (KR)
- (73) Assignee: **SAMSUNG ELECTRONICS CO., LTD.**, Suwon-si (KR)
- (*) Notice: This patent is subject to a terminal disclaimer.
- (**) Term: **15 Years**
- (21) Appl. No.: **29/685,133**
- (22) Filed: **Mar. 26, 2019**

Related U.S. Application Data

- (63) Continuation of application No. 29/623,660, filed on Oct. 26, 2017.

Foreign Application Priority Data

- Apr. 28, 2017 (KR) 30-2017-0020106

CLAIM

The ornamental design for an electronic device, as shown and described.

DESCRIPTION

FIG. 1 is a front perspective view of an electronic device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The dashed broken lines in the drawings illustrate portions of the electronic device that form no part of the claimed design.

1 Claim, 8 Drawing Sheets(56)
